HYGROMETER

Jean De Rayville, New York, N. Y.

Application February 1, 1936, Serial No. 61,936

13 Claims. (Cl. 73—337)

The invention relates to hygrometers.

One of the objects of this invention is to provide a simple, practical and dependable device for indicating, or responding to, the factor of humidity of an atmosphere. Another object is to provide a hygrometer construction that will be simple and inexpensive to manufacture, capable of ease and rapidity of assembly and capable of being quickly and easily set or adjusted. Another object is to provide a construction of the above-mentioned character in which acceptable accuracy of indication or response to the humidity factor of an atmosphere may be achieved without requiring high or expensive degree of precision in manufacture. Another object is to provide an instrument of the above-mentioned character which will be substantially self-adjusting under certain conditions liable to be met with in practice. Another object is to provide an instrument of the above-mentioned character in which the various degrees of humidity to which it is responsive may be conveniently and easily indicated visually. Another object is to provide an instrument of the above-mentioned character which in general will be well adapted for inexpensive and quantity production in which various parts may be easily and inexpensively manufactured and assembled and which will also have the features of adequate strength and durability of construction and of adequate reliability of action. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which is shown one of the various possible embodiments of my invention—

Figure 1 is a front elevation of the instrument on a small scale, certain parts being broken away;

Figure 2 is a front elevation as seen with the front or cover and certain other parts removed, thereby to show certain interior parts more clearly;

Figure 3 is a sectional view as seen substantially along the line 3—3 of Figure 1, the plane of the section being also indicated at 3—3 of Figure 2 in order thereby better to correlate these three figures, certain parts of Figure 3, however, being shown in elevation;

Figure 4 is a fragmentary perspective view

showing the construction of certain elements of the instrument structure;

Figure 5 is a sectional view as seen along the line 5—5 of Figure 3, and

Figure 6 is a fragmentary detached view showing the construction of the sliding connection between certain of the parts.

Similar reference characters refer to similar parts throughout the several views in the drawing.

Referring now to the drawing and more particularly to Figures 1 and 3, the instrument has a suitable enclosure which is preferably cylindrical in shape and preferably comprises a casing generally indicated at 10 (Figure 3), the casing having cylindrical walls 11 closed at one end by an end wall 12, the casing 10 being preferably of sheet metal and hence lending itself readily to drawing or stamping into the desired shape; the end wall 12 would appear as the rear wall (not shown) in Figure 1. The cylindrical side wall 11 has secured to it a suitable standard or base 13 (Figure 1) by means of which the instrument may be stood up as on any suitable horizontal supporting surface, such as a table, shelf, or the like, though, of course, any other suitable means may be employed for mounting or supporting the ultimate instrument where and in any manner desired.

The forward portions of the cylindrical side walls 11, appearing as the upper portions in Figure 3, are stepped or flanged as at 14 in order telescopically to seat thereabout the cylindrical side flange 15 of the casing cover generally indicated at 16, the latter having a disk-like front face 17 forming, in effect, the front end wall of the enclosure 10—16. The cover 16 is also preferably made of sheet metal and may be easily stamped or drawn into the form described.

The enclosure portions 10 and 16 are preferably detachably connected and, moreover, and preferably, in a manner to permit a certain amount of rotary adjustment or movement therebetween; for this purpose two or more bayonet joints indicated at 18 and 19 in Figure 1 may be employed, the respective parts of which being related to the flanges 14 and 15 in any suitable or known manner. Thereby assembly or disassembly of the enclosure portions 10 and 16 may easily be had while the pin and slot connections of the bayonet joints are made of such lengths, as will later be seen, as to permit the cover 16 to be manually adjusted or rotated relative to the casing 10, all for a purpose also later described.

At preferably the center of the disk-like rear

or end wall 12 (Figure 3) there is secured rigidly but preferably detachably a post 20, preferably of metal, and, as is better shown in Figure 5, the post 20 is provided with two diametrically opposed longitudinally extending slots 21 and 22. Into these slots are received the moisture- or humidity-responsive elements 23 and 24, respectively, being secured to the post 20 in any suitable manner as, for example, by wedging them into the slots or by clamping them therein, such action being achievable by pressing the opposed walls of the slots toward each other. As will later be seen, numerous features of my invention can be carried out by the use of only one of the elements 23, 24 but because, due to certain other features of my invention, I am enabled to bring into action forces acting by way of a mechanical couple, I therefore prefer to employ, and hence I show in my preferred embodiment, two moisture-responsive or hygroscopic elements 23—24.

The latter elements are preferably each made of two coacting members differently responsive to changes in humidity, and in Figure 4 I have shown in fragmentary perspective a possible mode of construction of these elements. The elements are sheet-like in form or shape and each comprises two sheet members A and B secured together, face to face, as shown in Figure 4. For example, one sheet member, such as member A, may be of a relatively thin sheet of wood, the sheet being cut lengthwise of the grain and illustratively being of a thickness on the order of 0.01 inch. The wood employed may be any suitable wood that is suitably hygroscopic and initially is, for assembly purposes, treated to be substantially dry. The other element B may comprise any suitable bendable or flexible material that is non-hygroscopic; it may, for example, be waterproofed paper and the two members A—B are secured together face to face by any suitable adhesive that is non-hygroscopic. Preferably the material of element B has a temperature coefficient of expansion, as compared to that of the element A, that temperature changes have no or a negligible effect on the action of the combined elements. The member B, however, may also be of wood and in such case it is cut preferably thinner than member A, being of a thickness on the order of 0.001 inch, as compared to the above-described thickness of the wood member A, and being in such case a sheet of wood cut, however, lengthwise of the grain, the two members A—B being secured together back to back as above described.

Any suitable adhesive may be employed that is substantially non-hygroscopic, such as rubber cements, celluloid or cellulose cement compositions, adhesives such as are used in so-called "dry mounting" work, and the like. Where both members A and B are of wood, I prefer to employ holly wood. In any case, the parts A and B are secured together, preferably under pressure, but in such condition that they are free from moisture content and hence preferably oven dry.

The elements 23 and 24 are so related to the stationary or fixed post 20 that the grain of member A of each element runs in a direction parallel to the axis of the post 20, that axis being, as will later be clear, the axis about which the elements 23 and 24 curve or bend or flex under the effects of the moisture in the atmosphere. In Figure 3 the direction of the grain of member A of element 24 is clearly shown, as just described.

Where member B of these elements is made of wood, it is so related to the member A that its grain extends in the direction of a radius emanating

nating from the axis of the post 20, it being thus clear that the grains of members A and B of each of the elements 23, 24 extend transversely of each other. Thus, the grain of member B of element 23 is shown in Figure 3 as extending radially and that direction of grain is true also of the member B in back of the member A of element 24.

With this arrangement and construction of the elements 23, 24, the latter bend or warp or flex or curve about the axis of the post 20, thus giving the outer ends of the members 23, 24 a motion of translation along a curved path. This motion of translation is communicated in amplified form to certain indicating means to which reference might first be made before describing the manner and means in which such motion is transmitted.

Accordingly, and referring again to Figure 3, the face or end wall 17 of the cover 16 carries an inwardly directed stud 27, secured thereto in any suitable manner and substantially at its center, the axis of the stud 27 and the axis of the post 20 being in alinement or coincident, the stud 27 having a head 28. The stud 27 serves as a shaft for a bushing 29 to which is secured an elongated sheet metal cross-member generally indicated at 30, member 30 being thus rotatably mounted by bushing 29 upon the stud 27, its length, as is better shown in Figure 3, being slightly less than the inside diameter of the enclosure 10—16 so that it may freely rotate within the enclosure.

Its two arms, each to one side of the hub or bushing 29, are provided with radially extending slots 31, 32, as is better shown in Figure 2, for a purpose later to be set forth.

Resting upon the cross-member 30, as viewed in Figure 3, and thus positioned in front of the latter, as viewed in Figure 2, is a disk-like dial 33 of a diameter of less than that of the enclosure 10—16 (see Figure 3) and made of any suitable light sheet material, such as light sheet metal, suitable cardboard, celluloid, or the like, and it is apertured at its center so as to be received upon the bushing or hub 29 (Figure 3) relatively loosely; the dial 33 may thus be easily given a rotary movement relative to the hub or bushing 29 and hence relative to the cross-member 30.

The dial 33 is to be rotated or driven in response to rotary movement of the cross-member 30 and the driving connection between these two members is preferably a friction clutch type of connection constructed in any suitable manner to cause the cross-member 30 to swing or rotate the dial 33 but to slip or yield when the load becomes greater than that represented by the dial disk 33 alone, for a purpose later described. A suitable and illustrative driving connection of this type may comprise spring-like tongues 34 and 35 (Figures 1 and 3) attached to or integrally formed with the cross-member 30, the two tongues extending upwardly from the plane of the cross-member 30, as viewed in Figure 3, and being bent into overlapping relation with respect to the dial 33, the springiness of the tongues being so adjusted that the corresponding diametrically opposed peripheral portions of the dial are gripped between the tongues and the cross-member 30, frictionally, so that the dial 33 has to follow the rotary movements of the cross-member 30; however, if the dial 33 is physically halted or stopped, the cross-member 30 may continue to rotate but now relative to the halted disk 33, the tongues 34—35 permitting slippage to take place.

The dial 33 is provided with graduations throughout a suitable portion of its periphery, as shown in Figure 1, graduated from 0 to 100, 75

representing the possible range of humidity variations of the atmosphere, the numerical graduations representing percentage relative humidity or moisture content of the atmosphere. If desired, the central portions of the dial 33 may be cut out, as indicated in Figure 1, to decrease the weight of the dial, giving it a spoked effect, as shown.

The range of graduations from 0 to 100% on the dial 33 is, moreover, and preferably, divided into three areas or arcs, each of suitable extent and of a distinctive color. Thus, in Figure 1, the arcuate range C from 0 to about 40 may be colored red; the arcuate range D from about 40 to 60 may be colored white; and the arcuate range E from 60 to 100 may be colored blue.

These colored ranges and the graduations are made visible through the front wall 17 of the cover 16 by means of a window 36 (Figure 1) of suitable radial and arcuate extent and, furthermore, the front wall 17 carries two arrow heads 37, 38 pointed toward each other and aligned along a radius and exposed through the aperture 36, as shown in Figure 1, the aperture 36 being closed 25 by a suitable transparent member 39 which may be of glass, mica, celluloid, or the like.

As the dial 33 is thus rotated in back of the front wall 17 or is brought to a stop corresponding to the reaction of the elements 23, 24 to the moisture content of the atmosphere, the specific percentage indication on the dial may be read off or seen as indicated by the arrow heads 37-38 while, for more distant observation, the color of the particular range of the ranges C, D and E (Figure 2) is visible through the aperture 36 to give a general indication as to whether the humidity is subnormal, normal or abnormal.

Recurring now to the driving connection between the elements 23, 24 and the dial 33, reference may now be made to Figures 2 and 3 from which it will be seen that there are attached to the free ends of the elements 23 and 24 levers 43 and 44. These levers are made of any suitable light material, such as light or thin sheet metal, and are in general arcuate, as viewed in Figure 2, having an arcuate extent of roughly 90°. They are rigidly attached to the free ends of the elements 23, 24 preferably by means of U-shaped sheet metal portions 45 and 46, respectively (Figures 3 and 5), the latter being of sufficient strength or thickness so that their flanges can be pressed inwardly toward each other and thus dependably and securely clamp the respective elements therebetween, the levers 43 and 44 being rigidly secured thereto at their upper ends, as viewed in Figure 3.

The otherwise free or unanchored ends of the arcuate levers 43, 44 are provided with normally radially extending extensions 43^a and 44^a, respectively, substantially as shown in Figure 2, where the parts are all seen in their interrelations when the elements 23, 24 are still dry or correspond to a dry atmosphere. By means of these extensions 43^a and 44^a sliding connection is made with the slots 31 and 32, respectively, in any suitable manner, as, for example, is shown in the detached view of Figure 6; a pin 56 supported by the lever extension by a suitable device, such as the device 55 comprising two spring arms 55^a and 55^b that clamp the extension therebetween, engages in the slot and thus a sliding and pivotal connection is made with the extension of the arcuate lever. Both lever extensions are graduated so that the two devices 55 may be adjustably posi-

tioned therealong and to the same relative position.

Accordingly, as the elements 23, 24 bend or flex or warp in response to, for example, an increase in the moisture content in the atmosphere, the enclosure 10-16 having suitable openings 47 (Figure 3) to permit ingress of the atmosphere, the arcuate levers 43, 44 are given a composite motion which is the resultant of a movement of translation, in counterclockwise direction, as viewed in Figure 2, of the respective ends of the elements 23, 24, and a swinging inwardly toward the center of the mechanism in response to the bending of the elements 23, 24 and due to the rigid connection of the arcuate levers to their 15 respective moisture-responsive elements.

In Figure 2 the elements 23, 24 with their respective arcuate levers are shown in broken lines in the positions they occupy at the other extreme of response, namely to indicate 100% humidity, 20 and it will be seen that the arcuate levers cross each other, the one tending to be wrapped around or against the central axis of the mechanism on one side thereof and the other to the other side of that axis; and to permit the arcuate levers to 25 overlap or thus cross each other without interference, they are stepped as at 43^b and 44^b, respectively (see Figure 3).

And as the parts undergo a transition in one direction or the other from the two extreme positions shown in Figure 2, in response to corresponding changes in humidity, or undergo transition from either of these extremes to some intermediate position, the corresponding movement of the respective ends of the elements 23 and 24, as 35 well as degree or extent of their flexing, is amplified or multiplied by the coaction therewith of the arcuate levers 43, 44 in coaction again with the sliding connections of the extensions of the latter with the slotted cross-member 30, effecting 40 a rotation of the latter and hence a change in rotary position thereof to correspond to the particular flexing of the elements 23, 24 to a given moisture condition of the atmosphere to which the apparatus is exposed. And the cross-member 30 45 in turn determines the rotary position of the dial 33, with respect to the indicating or arrow heads 37, 38 and the aperture 36 in the front face of the instrument, as seen in Figure 1, the graduations of the dial being, of course, calibrated to suit the 50 characteristics of the elements 23, 24 and to compensate, if necessary, for any non-uniformity of motion transmission from the ends of the moisture-sensitive elements to the cross-member 30 and dial itself.

Referring now to Figure 1, the dial 33 has upstanding therefrom a radially extending stop member 48 positioned substantially as shown and it is adapted to coact with two stop members in the form of studs or pins 49 and 50 (Figures 1, 60 2 and 3) carried on the inner face of the front wall 17 of the cover member 16, projecting inwardly from the front wall 17 sufficiently to be positioned in the path of rotary movement of the stop member 48 as carried by the dial 33.

These stop members are so spaced that, when the dial 33 is rotated in clockwise direction, as viewed in Figure 1, to bring the zero indication on the dial in alinement with the arrow heads 37, 38, stop member 48 on the disk engages the stop member 49 and thus prevents overrunning of the dial, while rotation of the disk in counterclockwise direction to bring the other extreme of the dial, namely the 100% indication, in alinement with the arrow heads 37, 38, brings the 75

stop member 48 on the dial into abutting relation to the other stop member 50, thus preventing overrunning of the dial in that direction.

But this stoppage against overrunning of the dial is effective only upon the dial itself but imposes no strains upon the operating mechanism or upon the elements 23, 24, for these parts may overrun the slight amount that may be necessary because of the friction clutch connection between the cross-member 30 and the dial 33, as above described. Accordingly, when this stoppage comes into action, cross-member 30 may continue to move though this movement will be a slight one ordinarily, while the indicating dial 33 is held against movement. These actions take place to effect a self-adjustment to compensate for variations or non-uniformity, sometimes uncontrollable, in the manufacture of the clutch-sensitive elements for a quantity of instruments and thereby I am enabled to overcome such difficulties sometimes inherent in the materials employed and hence uncontrollable and hence also I am enabled to avoid the need for high precision of construction and manufacture. Thereby cost of production is materially lessened.

Furthermore, stoppage members 49 and 50 are carried by the cover member 16 which, it will be recalled, is rotatably adjustable with respect to the casing 10, due to the bayonet joints 18, 19 above described, and the arrow heads 31, 38 are likewise carried by the cover. Accordingly, upon initial assembly or if necessary during the subsequent action of the instrument, a relative rotary adjustment between the cover 16 and the casing 10 may be made to make certain that any overrunning or underrunning is the same at both extremes of dial or humidity indication. And since, for ordinary use, particularly for household use, it rarely if ever is necessary to have indications of 0 or 100% humidity of the atmosphere, due to the fact that these conditions rarely if ever occur in the atmosphere, I am by the above means enabled to achieve substantial correctness and accuracy of indication throughout the intermediate ranges within which, particularly in climatic conditions throughout the United States, atmospheric humidity conditions generally fall.

Thus, it will be seen that there has been provided in this invention an apparatus in which the various objects hereinbefore noted together with many thoroughly practical advantages are successfully achieved.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. In an instrument of the character described, in combination, an enclosure comprising a casing part and a cover part, means interrelating said parts for relative rotary adjustment, said cover part having a window therein and having two stop members, a dial bearing visual indications rotatably carried by said cover part for presenting an indication to said window according to the rotary position of the dial, said dial having a stop member coacting alternately with said two stop members, the latter being positioned in the path of movement of said dial stop member to prevent the dial from overrunning at its two extremes of movement, a rotatable mem-

ber, means forming a driving connection between the latter and said dial, said driving connection being capable of yielding or slipping upon halting of the rotary movement of said dial by said stop members, said rotary member being elongated and extending diametrically of said dial, means supported in said casing and comprising two radially extending moisture-sensitive elements capable of changing their curvatures in response to changes in moisture content of the atmosphere, a pair of arcuate levers each rigidly attached to the end of one of said elements and to be moved and swung in response to bending of the latter, and means forming sliding connections between the respective free ends of said arcuate levers and said rotary member, whereby movement of said levers is transformed to rotary movement of said rotary member.

2. In an instrument of the character described, in combination, an enclosure comprising a casing part and a cover part, means interrelating said parts for relative rotary adjustment, said cover part having a window therein and having two stop members, a dial bearing visual indications rotatably carried by said cover part for presenting an indication to said window according to the rotary position of the dial, said dial having a stop member coacting alternately with said two stop members, the latter being positioned in the path of movement of said dial stop member to prevent the dial from overrunning at its two extremes of movement, a rotatable member, means forming a driving connection between the latter and said dial, said driving connection being capable of yielding or slipping upon halting of the rotary movement of said dial by said stop members, said rotary member being elongated and extending diametrically of said dial, means supported in said casing and comprising two radially extending moisture-sensitive elements capable of changing their curvatures in response to changes in moisture content of the atmosphere, and motion-amplifying means forming connections between said elements and radial portions of said rotary member for causing rotary movement of the latter in response to curving of said elements.

3. In an instrument of the character described, in combination, an enclosure comprising a casing part and a cover part, means interrelating said parts for relative rotary adjustment, said cover part having a window therein and having two stop members, a dial bearing visual indications rotatably carried by said cover part for presenting an indication to said window according to the rotary position of the dial, said dial having a stop member coacting alternately with said two stop members, the latter being positioned in the path of movement of said dial stop member to prevent the dial from overrunning at its two extremes of movement, a rotatable member, means forming a driving connection between the latter and said dial, said driving connection being capable of yielding or slipping upon halting of the rotary movement of said dial by said stop members, said rotary member being elongated and extending diametrically of said dial, means supported in said casing and comprising two radially extending moisture-sensitive elements capable of changing their curvatures in response to changes in moisture content of the atmosphere, said rotary member having substantially radially extending slots extending on both sides of its axis, and driving connections having slideable engagement with said slots for causing said

- rotary member to respond to flexing of said elements in response to changes in moisture content of the latter.
4. In an instrument of the character described, in combination, an enclosure comprising a casting part and a cover part, means interrelating said parts for relative rotary adjustment, said cover part having a window therein and having two stop members, a dial bearing visual indications rotatably carried by said cover part for presenting an indication to said window according to the rotary position of the dial, said dial having a stop member coacting alternately with said two stop members, the latter being positioned 10 in the path of movement of said dial stop member to prevent the dial from overrunning at its two extremes of movement, a rotatable member, means forming a driving connection between the latter and said dial, said driving connection being 15 capable of yielding or slipping upon halting of the rotary movement of said dial by said stop members, said rotary member being elongated and extending diametrically of said dial, means supported in said casing and comprising two 20 radially extending moisture-sensitive elements capable of changing their curvatures in response to changes in moisture content of the atmosphere, said rotary member having substantially radially extending slots on both sides of its axis, arcuate 25 levers each anchored at its one end to a free end of one of said elements, and means coacting with said slots and forming respectively sliding connections between the other ends of said levers and said rotary member.
5. In an instrument of the character described, in combination, an enclosure comprising a casting part and a cover part, means interrelating said parts for relative rotary adjustment, said cover part having a window therein and having two stop members, a dial bearing visual indications 30 rotatably carried by said cover part for presenting an indication to said window according to the rotary position of the dial, said dial having a stop member coacting alternately with said two stop members, the latter being positioned 35 in the path of movement of said dial stop member to prevent the dial from overrunning at its two extremes of movement, means constructed to exert a force in response to change in its moisture content, means mounting said means in said casing, and mechanism including an overload clutch 40 means for changing the rotary position of said dial in response to changes in said force.
6. In an instrument of the character described, in combination, an enclosure comprising a casting part and a cover part, means interrelating said parts for relative rotary adjustment, said cover part having a window therein and having two stop members, a dial bearing visual indications 45 rotatably carried by said cover part for presenting an indication to said window according to the rotary position of the dial, said dial having a stop member coacting alternately with said two stop members, the latter being positioned 50 in the path of movement of said dial stop member to prevent the dial from overrunning at its two extremes of movement, a movable member, means forming a yieldable driving connection between said movable member and said dial, means 55 constructed to change its physical shape in response to changes in moisture content of the atmosphere, means mounting said last-mentioned means in said casing, and means forming a driving connection between said moisture-responsive 60 means and said movable member to effect move- 65 ment of the latter in response to change in shape of the former.
7. In an instrument of the character described, in combination, a supporting frame, a rotary member rotatably carried by said frame and having portions extending to each side of its axis, means supported by said frame and comprising two moisture-sensitive elements capable of changing their curvatures in response to changes in moisture content of the atmosphere, a pair of 10 levers each rigidly attached to the end of one of said elements so as to be moved and swung in response to bending of the latter, and means forming sliding connections between the respective free ends of said levers and said portions of 15 said rotary member for effecting rotation of the latter in response to the action of said moisture-sensitive elements.
8. An instrument as claimed in claim 7 in which said frame carries also a scale and datum 20 means, one of which is movable relative to the other, and means forming a connection between the one that is movable and said rotary member.
9. An instrument as claimed in claim 7 in which said frame carries datum means and scale 25 or dial means rotatable with respect to said datum means, and means forming a driving connection between said scale means and said rotatable member.
10. A condition-sensitive unit comprising a 30 mounting post having a plurality of condition-sensitive elements mounted thereon and extending radially therefrom each of said elements having rigidly mounted on the end thereof an arcuate lever arm which has a radially extending 35 portion, a pin-like member adjustably mounted upon each of said radial portions, a pivotal element mounted so as to rotate upon an axis in line with said mounting post and having a plurality of slots therein into one of which each of 40 said pins may move freely, whereby said pivotal element is controlled in its rotary movement by said condition-sensitive elements.
11. In an instrument of the character described, in combination, a condition-responsive 45 unit, a scale and datum means one of which is mounted upon an adjustable member and the other of which is a movable means and controlled by said condition-responsive unit, one of said means also being provided with two stops 50 and the other of said means being provided with a single stop, said stops cooperating so as to allow limited movement between said scale and datum means, and a clutch mechanism, said movable means being controlled by said condition- 55 responsive means through said clutch mechanism, and said stops and clutch mechanism cooperate so as to automatically readjust said movable means under certain predetermined conditions.
12. In an instrument of the character described, an enclosure comprising a casing part and a cover part, said cover part having a window therein and being adjustable upon said casing part, a condition-responsive unit within 60 said enclosure comprising a plurality of condition-sensitive elements mounted upon a control post in said casing, each of said elements extending radially from said post and having mounted upon the free end thereof a rigid arm 65 which carries a pin, a scale-carrying element rotatably mounted and adjustably carrying a scale, said scale-carrying element being provided with a plurality of slots within each of which one of said pins may move freely, whereby said scale is 70 75

normally controlled by the cooperative action of said plurality of condition-responsive elements.

13. In apparatus of the class described, the combination of, an indicating sheet, a clutch mechanism, a condition-sensitive element comprising two strips each of which has a flat face, said strips being attached to each other in face-

to-face relationship, said element being mounted with a free end, said free end being attached by means of said clutch mechanism to said indicating sheet, and stop means operatively associated with said indicating sheet to limit the movement thereof and adjust said indicating sheet. 5

JEAN DE RAYVILLE.
